UNITED STATES PATENT OFFICE.

VINCENT W. WILSON, OF PAWTUCKET, RHODE ISLAND.

DESIGN FOR A GAME-FRAME.

SPECIFICATION forming part of Design No. 31,418, dated August 15, 1899.

Application filed May 10, 1899. Serial No. 716,292. Term of patent 3½ years.

To all whom it may concern:

Be it known that I, VINCENT W. WILSON, a citizen of the United States, residing at Pawtucket, in the State of Rhode Island, have invented and produced a new and original Design for a Game-Frame, of which the following is a specification, reference being had to the accompanying drawings, forming a part thereof.

- Figure 1 represents a side elevation of the frame, showing my new design. Fig. 2 represents a vertical section taken in the line 2 2 of Fig. 1.

My design includes a horizontal base-plate or disk A, the uprights B B and C, attached to the base-plate, and the cross-bars D D D, arranged transversely of the uprights with equal spaces *a a* between them, the space *b* between the lower cross-bar D and the base-plate A being made of greater width than the spaces *a*. The cross-bars D D are made of elongated cross-section and having their wide

sides arranged parallel with the line of the uprights, as shown in Fig. 2.

The leading feature of my design consists in the ladder-like construction composed of the uprights extending upward from the base-plate or disk, the series of transverse bars having uniform open spaces between them, and an open space between the base-plate and the lower transverse bar greater than that of the open spaces between the bars, the said cross-bars being arranged widthwise in the line of the uprights.

Having described my new design, what I claim as my invention, and desire to secure by Letters Patent, is—

The design for a game-frame herein shown and described.

VINCENT W. WILSON.
